John Skinner

UNITED STATES PATENT OFFICE.

JOHN SKINNER, OF NEWMAN, ILLINOIS.

ROAD GRADER AND LEVELER.

SPECIFICATION forming part of Letters Patent No. 364,445, dated June 7, 1887.

Application filed March 20, 1886. Serial No. 196,016. (No model.)

To all whom it may concern:

Be it known that I, JOHN SKINNER, of Newman, in the county of Douglas and State of Illinois, have invented a new and useful Improvement in the Road Grader and Leveler for which I received Letters Patent No. 324,178, dated August 11, 1885, and the following is a specification of my improvement of said machine.

10 The object of my invention is to facilitate and improve the method of elevating and lowering the frame-work carrying the harrow-teeth and scraper of my road grader and leveler.

15 In the accompanying drawings, in which similar letters of reference indicate like parts, Figure 1 is a perspective view of the entire machine adjusted as required when in actual operation. Fig. 2 is a perspective detail view.

20 A A A A are parallel beams, in which harrow-teeth are fixed.

25 B B is a strong board in the rear of and parallel with the harrow-beams A A A A and connected with harrow-beams by arched cross-beams D D D.

C C is a curved steel plate attached to the front of the board B B, and forming the scraper and mold-board.

30 As a means for raising the scraper B C off the ground or holding it fixed in any adjustment relative to the surface it works on, I employ elbow-levers E, which are pivoted at their angles and carry wheels O in the slotted ends of their lower and shorter arms. The 35 said levers are pivoted to toothed segments K, which are hinged vertically to suitable brackets, k, bolted to the rear side of scraper-board B, so that they will enable the parts E O to turn laterally according to the direction of motion of the machine.

40 Sliding spring-actuated pawls L are applied to the levers E on their upper sides, and adapted to engage with the teeth of segments K, so as to lock said levers in any desired adjustment. The means for elevating the front portion of the machine—to wit, the toothed bars A A—are the wheel X and a system of levers and rods arranged in the middle of the machine. The standard of wheel X is swiveled in the shorter arm of 45 the elbow-lever Y, and hence operates as a

caster when in contact with the ground. The longer arm of said lever Y extends back and is pivoted to the central cross-beam, D.

A slotted lever, J, is pivoted at I to the center cross-beam, D, through the slot of 55 which lever is rigidly fastened a toothed segment or ratchet, K, to the center cross-beam, D. Pivoted to the lever J is a slotted arm or bar, S, the other end of same being pivoted at U to the L-shaped slotted lever Z, the latter being pivoted at M to the slotted lever Y, and also pivoted at W to the upper end of the slotted arm Q. The latter is attached at its lower end to the front harrow-beam, A A, at P.

55 The chains fastened to the front harrow-beam near its ends are simply draft-chains, to which the motive power is attached.

When it is desired to elevate the road grader and leveler, in order to pass over bridges, culverts, street-crossings, or any other obstacle, or when it is desired to transport the machine without operating it, the harrow-teeth and scraper may be lifted from the ground by moving the levers E E and J backward and downward, and permitting the spring-pawls L L L to engage the toothed segments K K K. These place the wheels O O and X in contact with the ground, so as to elevate the machine to any desired height and support the same.

80 To lower the machine, press the spring-pawls L L L, so as to disengage the toothed segments, and raise the ends of the levers E E and J as far as desired, and then permit the spring-pawls to engage the toothed segments. The 85 wheels may be raised clear of the ground, if desired, by simply pressing the levers sufficiently upward and forward while the toothed segments are disengaged.

I claim as my invention—

90 1. The combination, with the road grader and scraper, of toothed segments K, hinged, as specified, so as to swing laterally, the elbow-levers having wheels attached, and locking-pawls arranged to engage said segments, as shown and described.

95 2. The combination, with the road scraper and grader, of the system of levers Y J and arms connecting them, the wheel X, the locking-pawl, and a toothed segment attached to 100

the frame of the machine, as shown and described.

3. The combination, with the parallel toothed bars A, the scraper C, and the cross-bars D, to which said parts are rigidly attached, of the rear adjusting devices—to wit, the toothed segments, pivoted levers, pawls, and wheels attached to said scraper—and the front adjust-

ing devices consisting of a wheel and the system of connected levers Y J, all arranged substantially as set forth.

JOHN SKINNER.
